VARIABLE CONDENSER

John J. Aurynger, Takoma Park, Md.

Application November 30, 1932
Serial No. 645,076

4 Claims. (Cl. 175—41.5)

The invention comprises a manually operated spacing device the object of which is two-fold: First, a positively charged section of a polycondenser is placed alongside a negatively charged section in order to balance potential charges between the rotor and stator of each section and to counterbalance the potential between adjacent sections of both the rotor and stator of each section. Secondly, to provide a spacing device between adjacent sections of the polycondenser in order to create a control on the induced capacity and lessen the superimposed capacities in adjacent sections caused by the proximity of the sections of the polycondenser forming the unit.

The invention is an improvement over the filleted joint in Fig. 11 of my patent for two-condensers-in-one, Patent # 1,608,472. My former invention dealt with electric conductors in the same area of a dielectric medium. In the present invention the internal functions of condensers is dealt with and improved. A detachably connected spacing device increases the space between sections or draws the sections closer together, causing a decrease or an increase in the capacity, respectively. The capacity can not be decreased below that existing between rotor and stator of a section. A capacity greater than that existing between rotor and stator of a section is undesirable and the object of the spacing device is to separate adjacent sections of the polycondenser so as to minimize overlapping of capacities. Further proof that it is the same area of a dielectric medium may be found in the antenna current permeating all sections of the polycondenser.

The uses to which a polycondenser may be put are likened to the adding machine. By suitable synchronous charges and phase charges through the dielectric medium the pick-up and output of the polycondenser will be addition, subtraction, multiplication and division of voltages. With a polycondenser connected in one type of parallel circuit the use with the outside circuit is addition, another parallel connection gives neutralization or subtraction of charges, and feed-back and series circuits give multiplication and division of voltages. These uses are the result of considering the polycondenser as a single unit without shielding between sections. Modern shielding is not the isolation problem generally conceded, but is the application of electric charges through the dielectric medium. Shielding condensers is often accomplished by inserting a plate having the polarity of the rotor plates between stator sections. Other ways connect the intermediate

plate with the ground, thus giving a charge to the plate opposite in sign to the antenna current in each section of the polycondenser. This is a conclusive proof that it is the same area of the dielectric medium. The term to express these extremes of potential is called the diametrical order of applying charges.

Referring to the drawing, Fig. 1 represents two sections of a polycondenser, detachably connected in respect to each other, having a spacing device to regulate capacity between sections by increasing or decreasing the space between sections as the case may be. The potential on one set of rotor plates is connected to the potential on the plates composing a stator section of adjacent sections by dividing the middle end piece into two parts.

Fig. 2 is a cross-section view of Figure 1, giving a side view of the spacing device and showing how the electrical connections are made between the rotor plates of one section and the stator plates of an adjoining section.

Fig. 3 is a special joint placed on the spindle and is a part of the spacing device. Its purpose is to keep the rotor spindles in alignment by means of ridges on the tongue and groove of the spacer.

The drawing shows a polycondenser having only two sections; but the invention places no limit as to the number of sections that a polycondenser may have.

Referring to the drawing by letter, in Fig. 1, S represents the spindle in two sections, detachably connected at the center, each half supporting separate sets of rotor plates "A" and insulated from each other at the point of junction. The spindle can be made to fit into any bearing of the conventional type and are held in place by three end pieces "E", two at the extremes and one in the center at the end of a section. These end plates also form the electrical terminals of the rotor plates. The frames "E" of which there are one for each insulated section of the rotor, or there may be two, one at each end of the insulated sections, hold the rotor elements in alignment, each frame "E" situated at the end of the rotor section. The frame "E" is insulated from the stator element of the rotor section to which it is electrically connected. The lugs "L" on the rail "R" are insulated from the frame "E" and the frame "E" and lug "L" are riveted together. The insulation is extended so as to cover the space surrounding the rivet in order to insulate the rivet from the frame. The lugs "L" of which there may be several may be made by slots pressed

in the rails. "R" may be electrically as well as mechanically connected to the stator, there being a separate rail for each section. Each stator is provided with four "R" rails, one on each corner; each rail is provided with a slot "P" near each end. The "R" rails are U shape for the insertion of insulation strips "I", between condenser sections which connect adjacent condenser sections by extending from the rails on one section to the rails on the adjacent section. When the spacing distance between two adjacent condenser sections has been determined, the screws in the insulation strips which pass through the slots in the rails are tightened in order to hold the sections in place. The screws are marked with an "X".

The end pieces "E" are hollow frames in order that while given the same potential as the rotor plates they lie nearest to the stator section without affecting to any noticeable degree the potential of the stator which has the opposite sign as the rotor of that section. The portion of the end piece "E" that is cut out to form the frame "E" is fastened to the stator of the adjacent section and when the sections are close together the center section will fit into its frame. The panel section "E'" is joined to the left hand section permanently through the fastening with the rails "R". The "E'" panel moves with the left hand section when the position of the nuts "N" on screw "T" are altered to vary the spacing between "E" and "E'". The capacity of the frame "E" is negligible. This center section is designated "E'" and is not needed on the extreme ends.

The stator sections are two in number and the plates comprising them are lettered "B". The plates comprising each stator section are separately joined together. In order to form a unit the "R" rails and insulation strips "I" keep the sections in alignment.

"E'" represents the movable section of the end piece "E". "E'" is fastened to the left stator section, while "E" the frame is fastened to the right stator section. The movable section and the frame are joined by a threaded screw "T".

The cross-section Figure No. 2 is lettered identically as Fig. 1 and further description would be identical. A better view of the joint is had than in Fig. 1, also the end piece at the center is more clearly shown.

An adjustment is made as follows: After the screws in the insulation strip "I" are loosened in the slots "P", the nuts "N" on the thread screw "T" which is fastened to the end frame "E" and "E'", are tightened. There may be two of these, one on each side of the condenser. The movable section of the end frame "E'" moves forward and fits into the space in the frame "E". When the capacity has been adjusted so that the radio set is in tune the screws in the strip "I" can be tightened in the slots "P" making the set space between sections permanent. No trimming condenser is required. If the adjustment requires the condenser sections to be drawn apart the same procedure is followed with the exception of the nuts "N" which are turned in the opposite direction on the threaded screw "T".

One end of the spindle "S" is provided with a prong or tongue "V" which fits into a groove in the end of the spindle of the adjacent section. The surfaces should be insulated from each other so that no electricity can pass from one section to another. This can be done by having an insulating surface as bakelite covering the

metal parts. "C" holds the condenser plates together in units. The "U" rails hold the sections together. "C" represents bolts holding the plates of the stator section together, dividing the stator into sections similar in character to the use made of the insulation between the sections of the rotor. The invention is not limited to the use of bolts but any suitable means for holding the plates together may be used. The plates may also be joined to the rails "R". While "C" is shown as not connecting "E" with the other plates in the section the results are the same if "E'" is joined by means of "C" as when "E" is joined to rails "R".

Fig. 3 represents another form of groove similar to the joint in Fig. 2, but the materials of which it is composed are arranged different. A bakelite body screws into the end of the spindle. The surfaces are reinforced by thin metal covers to facilitate contact and permanent structure. The grooves for alignment are on the inner surface of the contact metals.

S represents end of spindle and has a bakelite end piece screwed in containing a groove. The contact surfaces of the groove and the outer surface are reinforced by metal bands "M". The bakelite is represented by "D". The ridges are shown which facilitate alignment of rotor spindles.

I claim:

1. In a polycondenser consisting of a plurality of condenser sections longitudinally disposed with respect to each other, each of said sections comprising rotor and stator elements forming a rotor and stator unit for each section, said sections being electrically cross-connected by a hollow metal journal frame which is electrically connected to stator of one section and electrically connected to rotor unit of adjacent section, said metal journal frame cooperating with a metal panel also connected to the stator unit of said one section, and forming an element thereof, the spacing between said metal panel and said metal journal frame altered for controlling a secondary capacity formed by said panel and the end stator element of the oppositely charged stator unit of said adjacent section.

2. In a variable polycondenser, consisting of a plurality of condenser sections longitudinally disposed with respect to each other, each of said sections comprising rotor and stator elements forming a rotor and stator unit for each section, said sections being electrically cross-connected by a hollow metal journal frame which is electrically connected to stator of one section and electrically connected to rotor unit of adjacent section, said rotor units having a tongue and groove joint on shaft between said units, said tongue moving in said groove commensurate with the movement caused by a threaded screw attachment between said condenser sections, said joint combining metal and insulating materials for insulating adjacent units of said rotor, said stator units provided with U-shaped rails fitted with insulating strips for holding said units together, screws in said insulating strips fitted in slots in said rails as described.

3. In a variable polycondenser, consisting of a plurality of condenser sections longitudinally disposed with respect to each other, each section comprising journal frames at ends thereof for supporting rotor, each of said sections comprising rotor and stator elements forming a rotor and stator unit for each section, said sections being electrically cross-connected by an inter-

mediate metal journal frame which is electrically connected to stator of one section and electrically connected to rotor unit of adjacent section, said intermediate frame connected by means 5 of a screw and nut attachment to a plate of adjacent stator unit.

4. In a variable polycondenser consisting of a plurality of condenser sections longitudinally disposed with respect to each other, one section having 10 a plate-panel connected to stator and adjacent section having a journal frame, each of said sections comprising rotor and stator elements forming a rotor and stator unit for each section, said sections being electrically cross-con-

nected by a hollow metal journal frame which is electrically connected to stator of one section and electrically connected to rotor unit of adjacent section, said adjoining rotor units insulated 80 and detachably mechanically connected, said adjoining condenser sections having a screw and threaded nut attachment between plate-panel element of said one section and the said journal frame of said element forming end piece of rotor of adjacent section for regulating the secondary capacity formed between the two intermediately adjacent oppositely charged elements of said stators.
